UNITED STATES PATENT OFFICE.

ERIC BRANDQUIST, OF ORANGE, NEW JERSEY.

SPARK-PLUG.

1,213,581.

Specification of Letters Patent. Patented Jan. 23, 1917.

Application filed June 7, 1916. Serial No. 102,202.

To all whom it may concern:

Be it known that I, ERIC BRANDQUIST, a subject of the King of Sweden, and a resident of Orange, in the county of Essex and State of New Jersey, have invented a new and Improved Spark-Plug, of which the following is a full, clear, and exact description.

This invention relates to spark plugs and has for an object the provision of an improved arrangement whereby upon an inspection of the plug a person may see whether or not the same is properly sparking.

Another object in view is the provision of a plug in which a dead section is produced with one end extending exteriorly of the engine when the plug is in use, thus allowing the operator to see whether or not the plug is sparking without removing the plug.

Another object in view is to provide a plug with a switch at the exterior part thereof which may be opened and closed for producing a spark thereby determining whether or not the operating contacts are properly sparking.

A still further object in view is to provide a plug which may be screwed into the cylinder and held therein by a single threaded clamping member.

In the accompanying drawings:—Figure 1 is a longitudinal vertical section through a spark plug embodying the invention. Fig. 2 is a transverse sectional view through Fig. 1 on line 2—2. Fig. 3 is a fragmentary horizontal section through part of an engine cylinder, a slightly modified form of spark plug being shown in connection therewith. Fig. 4 discloses a further modified form of spark plug to that shown in Fig. 1. Fig. 5 is a side view of a modified form of spark plug to that shown in Fig. 1. Fig. 6 is a sectional view through Fig. 5 on line 6—6. Fig. 7 is a diagram showing part of an automobile in top plan and a system of wiring associated with the plug shown in Fig. 1, the same embodying another form of the invention. Fig. 8 is a detail fragmentary sectional view, showing one of the switches disclosed in Fig. 7.

Referring to the accompanying drawings by numerals, 1 indicates a casing for a spark plug which may be of the usual construction now commonly in use except that the threaded portion 2 is much shorter so that the lower part of the porcelain 3 may extend an appreciable distance into the cylinder. The

porcelain 3 is held in place by the usual packing nut 4, which nut has a contact pin 5 connected therewith, which pin is provided with an arc-shaped portion 6 so that the end 7 of pin 8 may be the same distance from its coacting pin even though the nut 4 has been turned slightly. The porcelain 3 is preferably made wider at the lower part so as to form a shoulder or offset portion 9 through which the pin 8 passes. It will be observed that the pin 8 is dead as it is not connected with the contact bar 10 or with the contact pin 5.

When the plug is in use the current will jump the gap 11 and also the gap 12 so that there will be a spark in the cylinder and one exteriorly of the cylinder. The exterior gap is provided especially to indicate whether or not the plug is properly sparking interiorly. By reason of the fact that the pin 8 is dead ordinarily, insures a spark in the gap 11 whenever there is a spark in gap 12. The lower end of the contact bar 10 and the lower end of pin 8 may be constructed in any desired way and spaced any desired distance apart. Connected with the upper end of the bar 10 by any suitable means is a wire 13 which is connected with a source of current, which source of current is grounded on the engine and being grounded on the engine energizes the contact pin 5 so that when the make and break is operated a spark will be properly produced at the gap 11 and also at the gap 12.

In operating an internal combustion engine a large part of the trouble is caused by poor sparking or the failure to spark and in order to ascertain whether or not the spark plug is operating various means must be used and quite often it is necessary to entirely remove the plug and test the same to see if it will spark. The construction shown in Fig. 1 and just described produces a spark gap of the usual or preferred size and in addition produces an arrangement which will allow the operator to readily ascertain whether or not the plug is operating properly without molesting the plug in the least. In this way much time is saved when going over an engine to ascertain where any particular trouble is located.

In case it is not desired to have a spark exteriorly of the engine, as for instance, gap 12, a slightly modified arrangement may be used, as shown in Figs. 5 and 6, wherein the usual interior spark at gap 11 is provided

while no exterior spark is produced until the knob 14 has been pulled. Knob 14 is connected to a rod 15 which extends into a transparent casing 16 which is preferably formed from glass and into which the contact 5 and the rod 8 project, as shown more particularly in Fig. 5. The rod 15 carries a shoulder 17 which is pressed against the end of the pin 8 continually by spring 18, said 10 spring acting against a washer 19 which may be held in position by pin 5 or may rest against the end of the container 16.

When the plug is in use the parts assume the position shown in Fig. 5; but in case it 15 should be desired to test the plug to see if the same is sparking, knob 14 will be grasped and the rod 15 pulled until there is a space between contact 17 and the rod 8, whereupon if the plug is properly sparking 20 a spark will jump across this space. If this occurs the operator knows the plug is properly operating and he may then go to the next plug and operate the same to see if it is properly sparking. In this way all of the 25 plugs may be tested quickly and easily without removal from the engine. If the plugs are all in good shape it is evident that any trouble is caused by something else than the plug.

30 In the preferred form shown in Fig. 1 or in the modified form shown in Fig. 5 the contact or pin 5 is connected with the clamping nut 4, but if desired this pin could be connected directly to the engine, as shown in 35 Fig. 4, and the porcelain 3 screwed directly into the engine, thus eliminating both the casing 1 and the nut 4. To do this the porcelain must be made from some material which will stand heat and which will be of 40 insulating material also. The member 3 has been described as porcelain but it will be understood that the same may be formed from any material which will resist heat and which will also insulate the bars 8 and 45 10, and therefore the word porcelain is intended to cover any of these materials which may be used.

A further modified form of the invention is shown in Fig. 3 wherein the body 1 is 50 eliminated and the nut 4 is screwed directly into the cylinder 20 for clamping the porcelain 3 in position, said porcelain being constructed as shown in Fig. 1.

In Figs. 7 and 8 is disclosed a still further modified arrangement in which the switching mechanism is arranged adjacent the driver's seat and an appreciable distance away from the engine so that the driver may test his plugs at any time. As shown in 60 these figures the contacts 5 are connected by wires 21 to contact posts 22 mounted in a block 23 of insulating material, as shown in

Fig. 8. A socket 24 is connected to each of the blocks 23 so as to engage the knife 25 which is pivotally mounted at 26 to the 65 binding post 27, which binding post is supported by block 23. Normally the knife switch 25 is closed but if it should be desired to test any plug the particular knife switch associated therewith is opened 70 slightly, as shown in Fig. 8, and if the plug is operating as it should a spark will jump from the socket 24 to the knife 25. If a spark is not produced at this point when the switch is slightly open the driver knows that 75 the plug is not properly sparking.

What I claim is:

1. In a spark plug of the character described, an insulating member provided with a bar extending therethrough, the inner end of the bar acting as a contact, an auxiliary bar extending through said insulating member arranged so that the inner end will act as a contact spaced from the first mentioned contact, and a ground member extending to near the upper end of said auxiliary bar, said ground member being arc-shaped at its upper end, the arc being formed so as to cause the distance between the ground member and the auxiliary bar to 85 continually remain the same regardless of the position of the auxiliary bar.

2. In a spark plug of the character described, an insulating member, a pair of bars extending therethrough, means for connecting one of said bars with the ground, said means comprising a switch formed by a reciprocating bar and a spring for holding said reciprocating bar in contact with one of the first mentioned bars, and a glass container surrounding said switch confining the spark produced when the switch is partially opened and the plug is in use.

3. In a spark plug of the character described, an insulating member provided with an enlargement on one side at the lower part, said enlargement extending through the casing of the plug, said enlargement forming a shoulder at the upper end spaced below the upper end of the insulating member, a bar extending through the insulating member and forming a contact at the lower end, an auxiliary bar extending through the enlargement and made of such a length that one end will project beyond said shoulder 110 and the other end will project beyond the enlargement for forming a second contact whereby said auxiliary bar remains dead until the circuit is closed, and a ground member connected with said casing and formed 115 with a member extending to a point adjacent the upper end of said auxiliary bar.

ERIC BRANDQUIST.
